(57) **CLAIM**

The ornamental design for container with a hinged lid, as shown and described.

DESCRIPTION

FIG. 1 is a perspective view of a first embodiment of a container with a hinged lid showing my new design, wherein the lid is closed;

FIG. 2 is a front view thereof;

FIG. 3 is a rear view thereof;

FIG. 4 is a left-side view thereof, the right-side view being a mirror image;

FIG. 5 is a top view thereof;

FIG. 6 is a bottom view thereof;

FIG. 7 is a perspective view of the first embodiment, wherein the lid is open;

FIG. 8 is a front view of a second embodiment of a container with a hinged lid showing my new design;

FIG. 9 is a rear view thereof;

FIG. 10 is a left-side view thereof, the right-side view being a mirror image;

FIG. 11 is a top view thereof;

FIG. 12 is a bottom view thereof;

FIG. 13 is a front view of a third embodiment of a container with a hinged lid showing my new design;

FIG. 14 is a rear view thereof;

FIG. 15 is a left-side view thereof, the right-side view being a mirror image;

FIG. 16 is a top view thereof;

FIG. 17 is a bottom view thereof;

FIG. 18 is an enlarged, front view of a fourth embodiment of a container with a hinged lid showing my new design;

FIG. 19 is an enlarged, rear view thereof;

FIG. 20 is an enlarged, left-side view thereof, the right-side view being a mirror image;

FIG. 21 is an enlarged, top view thereof;

FIG. 22 is an enlarged, bottom view thereof;

FIG. 23 is an enlarged, front view of a fifth embodiment of a container with a hinged lid showing my new design;

FIG. 24 is an enlarged, rear view thereof;

FIG. 25 is an enlarged, left-side view thereof, the right-side being a mirror image;

FIG. 26 is an enlarged, top view thereof; and,

FIG. 27 is an enlarged, bottom view thereof.

The jagged U-shaped broken lines surrounding the openings in the front and perspective views of the containers define boundaries between the claimed design and unclaimed subject matter and form no part of the claimed design.

The mesh material that may be visible through each of the somewhat U-shaped openings and through the holes in the mesh has been removed for clarity.
